(57) **CLAIM**

We Claim the ornamental design for a pentop computer, as shown and described.

DESCRIPTION

FIG. 1 is a front left bottom perspective view of a pentop computer showing my new design;

FIG. 2 is a front elevational view thereof;

FIG. 3 is a right side elevational view thereof, the left side elevational view being a mirror image thereof;

FIG. 4 is a rear elevational view thereof;

FIG. 5 is a top plan view thereof;

FIG. 6 is a bottom plan view thereof; and,

FIG. 7 is a front left bottom perspective view thereof, showing removal of the detachable portion for clarity of illustration.

The broken line showing of the writing tool in FIGS. 2 and 3, the connector receptacle in FIG. 5, and the cartridge component in FIG. 7 are for the purpose of illustrating unclaimed portions and form no part of the claimed design.

1 Claim, 3 Drawing Sheets
